UNITED STATES PATENT OFFICE.

HEYMAN ROSENBERG, OF NEW YORK, N. Y.

GAUGING APPARATUS.

Application filed April 19, 1922. Serial No. 555,311.

To all whom it may concern:

Be it known that I, HEYMAN ROSENBERG, a citizen of the United States, residing at New York, in the county of New York and State of New York, have invented certain new and useful Improvements in Gauging Apparatus; and I do hereby declare the following to be a full, clear, and exact description of the invention, such as will enable others skilled in the art to which it appertains to make and use the same.

This invention relates to improvements in measuring apparatus of the type especially adapted for co-operative use with a punch, and the primary object in view is the accurate and successive location of material relative to the punch for enabling the formation of apertures in the material in certain predetermined and exact relation to each other.

With this and further objects in view as will in part hereinafter become apparent and in part be stated, the invention comprises certain novel constructions, combinations and arrangements of parts as subsequently specified and claimed.

In the accompanying drawings,—

Figure 1 is a view in side elevation of an apparatus embodying the features of the present invention.

Figure 2 is a horizontal section therethrough taken on the plane indicated by line 2—2 of Figure 1, parts being seen in plan.

Figure 3 is a vertical, fragmentary section taken on the planes indicated by line 3—3 of Figure 2, and looking in the direction shown by the arrows, parts being seen in elevation.

Figure 4 is a transverse, vertical section through the die of the punch with the parts disposed for operating on straight sections of material, parts being broken away and parts seen in elevation.

Figure 5 is a fragmentary, side elevation of a slightly modified embodiment of the invention.

Figure 6 is a front elevation of the parts seen in Figure 5.

Figure 7 is a plan view thereof, the punch bit and connected parts being omitted.

Figure 8 is a horizontal, fragmentary section taken approximately on the plane indicated by line 8—8 of Figure 6.

Referring to the drawings by numerals, 1 indicates a punch frame having the usual outstanding die table 2 and upper arched

arm 3 carrying the guiding head 4 through which slidely extends the punch bar 5 carrying the detachable punch bit 6. The punch bar 5 is guided within the head 4 and held thereby against other than axial movement, and the upper end of the punch bar is pivoted at 7 between the side plates of an eccentric 8 carried by an operating lever 9, the lever being pivoted at 10 to a pair of links 12. The links 12 are arranged at the opposite sides of the head 4 and pivoted thereto at 13 so as to compensate for lateral movement of the eccentric 8 while enabling the eccentric to effect the wedging or camming thrust of the punch for producing the punching stroke of the punch bit 6. A stripper 14 is preferably employed and arched about the lower portion of the punch, and is carried by upstanding arms 15 arranged at the opposite sides of the head 4 and clamped thereto by plates 16, engaged by wing nuts 17 threaded onto laterally extending bolts passing through the respective plates 16.

The free end portion of the table 2 carries a removable die or tubular member 18, arranged co-axially of and adapted to co-operate with the bit 6. A set screw 19 is threaded through a portion of the table 2 and engages the die receiving sleeve 18' and detachably retains the die in place. The edges of the table 2 are preferably beveled to form slide bars 20 on which is slidely mounted the collar 21 of the arcuate stop 22. The collar 21 underhangs the table 2, but is open at its lower portion to accommodate the bracing fillet or web 24 connecting and formed integral with the base of frame 1 and the under face of table 2. A set screw 25 is threaded through the collar 21 and engages one of the slide bars 20 for locking the stop 22 in any given adjusted position.

The base of the frame 1 is formed with a squared passageway through which is slidely extended a similarly squared bar 26. It will be apparent, of course, that the bar 26 may be otherwise polysided or otherwise shaped in transverse section so long as possessing a contour corresponding to the transverse contour of the passage-way and so shaped as to prevent rotation of the bar. A set screw 27 threaded through a portion of the base of frame 1 engages bar 26 to lock the bar at various points of longitudinal adjustment. The outer or free end of bar

26 extends into a socket 28 in a preferably circular plate 29, the plate 29 being thickened at the place of the socket 28 for providing sufficient space therefor. An appropriate rivet, pin, or other securing means 30 is passed through the wall of the material about socket 28 and through the bar 26 for securing the parts together. The plate 29 has its upper face formed into a dial 10 provided with graduations 31 arranged to facilitate the location of certain angles as will be hereinafter described. The plate 29 is centrally apertured, as indicated at 32 in Figure 3, and a tubular bolt 34 extends 15 through said aperture and is engaged by a wing nut 35 for clamping the bolt to the plate. The head of bolt 34 is formed into a transverse sleeve 33 and a tubular upper standing sleeve 36 above the sleeve 33. A 20 gauging pin 37 extends adjustably throughout the length of the bolt 34 across the sleeve 33 and through the sleeve 36, and is retained at various adjusted positions by an appropriate thumb screw 38 threaded through a portion of sleeve 36. The pin 37 is preferably provided with a conical head 39 at its upper end.

The sleeve 33 is in the form of a square or other appropriately polysided passage-way through which slidably extends the gage bar 40 having a central, longitudinal slot 41 permitting the bar 40 to slide longitudinally through the sleeve 33, while the pin 37 extends transversely therethrough, the pin being accommodated in the slot 41. One end portion of gage bar 40 is provided with a stop 42, seen in Figures 2 and 4, for preventing the bar 40 from being accidentally withdrawn through the sleeve 33. A 40 gauging pin 43 extends through the opposite end portion of bar 40 from that having the stop 42, and a set screw 44 is threaded through a portion of the material of bar 40 into engagement with the pin 43 for locking 45 the pin in various positions of longitudinal adjustments. The upper end of pin 43 is provided with a conical head 45. Projecting from, and preferably formed integral with the sleeve 33 is a pointer 46 having its point extending on a line at right angles to the longitudinal axis of the bar 40, so that, when the pointer 46 is brought into line with any one of the graduation marks 31, the bar 40 will extend at right angles 50 to the line of that mark, and the graduations 31 are calculated accurately relatively to such right angle so as to cause a circle described about the axis of rotation of the pointer 46 (when rotated as hereinafter described) to be equally divided into arcs 55 varying in length according to the location of the particular graduation 31, each graduation being marked with a number indicating the number of arcs in a complete circle when tested or gaged by the bar 40

as located incident to the positioning of the pointer 46 in line with the given graduation 31.

In operation, the present improved instrument is designed to facilitate accurate division of circular plates or bodies into equal arcs, so that the bodies may be perforated with openings spaced accurately and uniformly, and this result may be accomplished without the use of a templet. 70 The apparatus is especially well adapted for use in perforating ceiling plates, canopies, and other fixtures for electric light equipment and other similar devices. As indicated in dotted lines in Figure 1, the work 47 may be any appropriate, substantially disc-shaped body in which a central aperture is first formed and the plate is arranged with the conical head 39 extending partway through the aperture. The work 80 47 is thereby centered relative to the punch and the operator punches a hole near the periphery of the work, and then turns the work angularly until the perforation surrounds and the work rests upon the head 90 45 of pin 43. Another perforation is then formed in the work 47, and the work is again turned, and so on until the circle has been completed. However, before the first aperture formed is placed over the head 45, the bar 40 will have been located angularly as required for insuring the number of apertures desired. To effect the accurate angular location for this result, it is only necessary for the operator to loosen the nut 35 and swing the bar 40 with the bolt 34 and sleeve 33 moving pivotally on the longitudinal axis of the pin 37 until the pointer 46 registers with the graduation 31 bearing that indicia indicating the number of apertures desired. If only four apertures are required, the bar 40 will be moved until the pointer 46 points at the graduation 31 bearing the digit 4, whereupon the bar 40 will extend at right angles 100 to the bar 26 and a circle described about the axis of rotation of the bar 40 and sleeve 33 will have an arc representing one-fourth of the circle lying between the axis of the bar 26 and the axis of the bar 40. As the 105 axis of the bit 6 is coincident with the axis of bar 26, and the axis of pin 43 is coincident with the axis of bar 40, the aperture surrounding the head 45 will center upon the head and thus locate the work 47 with the center of the aperture spaced from bit 6 one-fourth of the circumference of the circle described by the work. If a 110 less number of apertures than four is required, the angle between the bars 26 and 40 will be widened, and if a greater number, the angle will be reduced, the graduations 31 being placed for accurate location of the bar 40 according to the number of apertures required. It will be understood, 115 120 125 130

of course, that whenever the bar 40 is adjusted for gauging any given number of apertures, the nut 35 is tightened as soon as the pointer 46 is brought into register with the required graduation 31. It should also be understood that the pin 43 is kept lowered and out of the way until the first aperture near the peripheral portion of the work 47 has been formed and is to be placed upon the head 45. The pin 43 is then raised into place and the screw 44 tightened to hold the pin in its proper position.

While in Figures 1 and 2 the invention has been illustrated as used in conjunction with circular work, it is also as effectively useful for straight work, such as strips or sheets. The location of the parts, when operating in conjunction with straight work, is indicated in Figure 4. To bring the parts to this position from that shown in Figures 1 and 2, the set screw 27 is released and the bar 26 is slid inward until the axis of pin 37 is brought into register with the axis of die 18. To insure accurate registration, the head 39 of pin 37 is preferably inserted into the lower open end of the bore of die 18 and centered there by virtue of the conical form of the head 39. This position of the parts is indicated in Figure 4. When so positioned, the bar 26 is locked by the tightening of the set screw 27, and the pin 37 is then preferably lowered to leave the passageway of die 18 free for the discharge of blanks stamped from the work. The strip or sheet representing the work is indicated in dotted lines at 48 in Figure 4, and the operation, after the bar 26 with its plate 29 have been properly located, consists in adjusting the bar 20 longitudinally until the axis of pin 37 is located laterally of the axis of die 18 the exact distance required between centers of openings to be formed in work 48. Since the work is straight, the bar 40 must be set at right angles to the bar 26, and, therefore, the pointer 46 will be placed in register with the graduation 31 bearing the digit 4. The bar 40 being locked in this position against swinging movement by the tightening of the nut 35, the pin 43 is adjusted to the raised position indicated in Figure 4, and, the first perforation having been made in the work 48, the work 48 is moved over and placed with the head 45 of pin 43 extending through and centered in said perforation. The work 48 is then again perforated and moved over until the new perforation is placed for centering about the head 45, and the operation of perforating the work 48 is thus continued, the apertures formed by the punch bit 6 being spaced on centers equal to the distance between the axes of pin 43 and die 18. Of course, graduations may be placed on the bar 40 for indicating such distance, but for all practical purposes it is found sufficient to measure by

the use of a steel tape or other rule the distance from the tip of the head 45 to the centering point at the lower end of the punch bit 6. It should be observed, of course, that the bar 40, while free to slide within the sleeve 33, fits the sleeve sufficiently snugly to have the required friction for retaining the bar 40 in any given position of adjustment longitudinally. Should the wear of the parts reduce such friction sufficiently to necessitate other precaution, a set screw may be passed through the material of sleeve 33 into engagement with the bar 40.

In Figures 5 to 8 inclusive is illustrated the same invention as shown in the preceding figures with the centering pin carrying the dial head and with the gage bar bent at right angles for adapting the parts for use in gauging canopies and tubular and cylindrical structures. In these figures the same punch is employed and the same reference numerals are applied to the parts of the punch shown, and the same description applies. The same bar 26 is utilized with its plate 29, tubular bolt 34 having the transverse sleeve 33, and the upstanding sleeve or collar 36 provided with the set screw 38. These are the identical parts shown in the preceding figures and the pin 37' extends through and is retained in the tubular bolt 34 in the same manner as pin 37, but pin 37' instead of terminating with an upstanding conical head is provided at its upper end with a disc 29' having graduations 31' arranged to function as do the graduations 31 save that the graduations 31' are arranged on a vertically-disposed face instead of a horizontally-disposed face. A bolt 34' extends through the center of disc 29' and is engaged at its outer end by a wing nut 35' clamping a collar 49 against the outer face of the disc 29'. Collar 49 carries a pointer 46' designed to function in the same manner as pointer 46, except in a vertical plane instead of a horizontal one. The collar 49 is formed with a squared opening through which a squared portion of the bolt 34' extends, so that the pointer 46' will revolve with the bolt. The inner end portion of bolt 34' is formed into a head providing a transverse sleeve 33' adapted to function the same as sleeve 33 except for the difference in the planes, and the head is finished with a conically-pointed portion 39'. A gage bar 40' is slidably mounted through the sleeve 33' and intermediate its ends is bent to form a right angle arm 40'' on which is slidably mounted a sleeve 50 carrying a gauging pin 43' having a conical head 45'. A set screw 41' locks the sleeve 50 in any given adjusted position along the arm 40''. The work indicated by the canopy 51 is placed in position surrounding the outer end portion of the table 2 with the

inner end of the canopy abutting against the stop 22, the canopy having already had a centering aperture formed in its outer end. The bar 26 is slid inward or outward and the pin 37' upward or downward according to whether the work 51 is smaller or larger, until the conical point 39' is passed into the centering aperture in the outer end of the work 51, and the work is centered thereby. The gage bar 40' is then swung vertically until the pointer 46' indicates the particular graduation 31' bearing the digit representing the number of apertures to be punched in the work 51, the bar 40' being slid out far enough to have the arm 40" in position for having the head 45' clear of the work. An aperture is then punched in the work 51, and the work is then turned until the aperture just punched comes into line with the head 45', and the bar 40' is then slid inward until the head 45' centers itself in the aperture just punched in the work 51. The work is then again punched, the bar 40' slid back, the work revolved, and the second opening centered on the head 45', and the punching progresses until completed.

It should be obvious from the foregoing that canopies or other similar work 51 of a wide range of sizes may be thus punched with any number of apertures desired with accurately and uniformly spaced centers, the gauging apparatus being adjusted only when a different sized piece of work is introduced from that which has been operated upon.

Nut 35' is, of course, released whenever bar 40' is to be swung angularly, and is again tightened to clamp bolt 34' in the new position as soon as pointer 46' registers with the particular graduation 31' required.

It is clear also that while the invention has been illustrated as applied to a punching machine in the sense of a machine which cuts holes by a single punching stroke, it is just as applicable to an aperture-forming machine or marker of any other class.

An essential feature of construction in the embodying of the present invention, as should be apparent from the foregoing, is the provision of means co-operating with a punch or other marker for readily and accurately establishing or measuring the distance between the axes of an aperture punched in work and an aperture to be punched therein. Such means is preferably adjustable, so as to facilitate measurement of such axes where work is of different sizes, or where the apertures in one piece of work are to be of a different distance apart from those in another piece of work, or otherwise provide for indicating uniform distances with ease, speed and accuracy. When it is desired to save the labor of measurement by

some form of independent graduate, as a straight rule or a vernier, according to whether the work being operated upon is straight or curved, an appropriate graduate is provided on or relative to the distance-establishing means, (head 45 and connected parts in the embodiment seen in Figures 1 to 4 inclusive) which serves as an effective and accurate time-saver. In operating on curved or circular work, the distance-establishing means indicates accurately the length of an arc of a circle produced to intersect the axis of the aperture already punched and the axis of the aperture to be punched, such arc being of a length to terminate with said two axes. Such arc may, of course, be measured by its chord as well as by its own length, and, while with circular work the distance establishing means may thus be adjusted and measured on the chord instead of the arc, the relative angularity of a straight line produced to intersect the axis of the work and the axis of the punch to a straight line produced to intersect the axis of the work and the axis of the distance-establishing means will always form a basis for ready and accurate calculation of the proper position for the location of the distance-establishing means. Hence, such angularity is taken into account in the embodiments of the invention illustrated in the drawings, and the dial graduations in each case serve merely to enable accurately and easily varying such angularity with each required variation in the distance. Because it is usually desirable to have the apertures to be punched equally spaced apart on the circle or arc described by the work, the angularity indicated by the dials shown is such as to divide a circle intersecting the axes of two of such apertures into arcs of uniform length. The angularity is of such degree as to divide the circle into equal parts, but, if under any conditions, the user should desire the first and last apertures to be spaced a distance apart different from the distance between each two of all of the other apertures, he would place pointer 46 or 46', as the case may be, between two of the graduation marks 31 or 31' instead of in register with one of them. Uniformity in spacing would still occur between all apertures except the first and last.

What is claimed is:—

1. In gauging apparatus, the combination, with a punch or the like, of an adjustable work support, distance-indicating means adjustable laterally of the support, and work-locating means carried by the distance-indicating means.
2. In gauging apparatus, the combination, with a punch or the like, of work-centering means co-operating therewith, and distance-

- indicating means adjustable laterally and movable angularly of the work-centering means.
3. In gauging apparatus, the combination, with a punch or the like, of work-centering means movable toward and away from the punch, and distance-indicating means movable laterally and angularly of the work-centering means.
- 10 4. In gauging apparatus, the combination, with a punch or the like, of work-centering means movable toward and away from the punch, distance-indicating means movable laterally and angularly of the work-centering means, and means for indicating the degrees of angular movement thereof.
5. In gauging apparatus, the combination, with a punch or the like, of work-centering means movable toward and away from the punch, and distance-indicating means movable angularly of the work-centering means.
- 20 6. In gauging apparatus, the combination, with a punch or the like, of work-centering means movable toward and away from the punch, distance-indicating means movable angularly of the work-centering means, and means for indicating the degrees of angular movement thereof.
7. In gauging apparatus, the combination, with a punch or the like, of an adjustable work support, and centering means carried thereby in position to successively engage apertures in the work formed by the punch, the support being adapted to sustain the work in a manner enabling angular adjustment thereof for such successive engagements.
- 30 8. In gauging apparatus, the combination, with a punch or the like, of work-centering means co-operating therewith, and distance-indicating means movable angularly of the work-centering means.
- 40 9. In gauging apparatus, the combination, with a punch or the like, of slidingly mounted work-centering means, and distance-indicating means pivoted to swing about the axis of the work-centering means.
- 45 10. In gauging apparatus, the combination, with a punch or the like, of slidingly mounted work-centering means, and distance-indicating means pivoted to swing about the axis of the work-centering means and mounted to slide across the line of its pivot.
- 50 55 11. In gauging apparatus, the combination, with a punch or the like, of distance-indicating means movable relative thereto for measuring arcs of a circle produced to intersect two given points on work acted upon by the punch.
- 60 12. In gauging apparatus, the combination, with a punch or the like, of distance-indicating means movable relative thereto for measuring arcs of a circle produced to
- intersect two given points on work acted upon by the punch, and means for indicating successive locations of the distance-indicating means for measuring one arc in each instance of arcs of equal length making up said circle.
- 70 13. In gauging apparatus, the combination, with a punch or the like, of distance-indicating means movable relative thereto for measuring arcs of a circle produced to intersect two given points on work acted upon by the punch, the distance-indicating means being slidingly mounted.
- 75 14. In gauging apparatus, the combination, with a punch or the like, of distance-indicating means movable relative thereto for measuring arcs of a circle produced to intersect two given points on work acted upon by the punch, the distance-indicating means being pivotally mounted.
- 80 15. In gauging apparatus, the combination, with a punch or the like, of distance-indicating means movable relative thereto for measuring arcs of a circle produced to intersect two given points on work acted upon by the punch, the distance-indicating means being slidingly and pivotally mounted.
- 85 16. In gauging apparatus, the combination, with a punch or the like, of work-centering means therefor, distance-indicating means pivotally mounted relative to the work-centering means, and a dial for indicating the angularity of the distance-indicating means.
- 90 17. In gauging apparatus, the combination, with a punch or the like, of work-centering means therefor, distance-indicating means pivotally mounted relative to the work-centering means, and a dial for indicating the angularity of the distance-indicating means, the dial bearing graduations for indicating those relative angles of the indicating means which divide into arcs of uniform length a circle produced about the axis of the centering means.
- 95 100 18. In gauging apparatus, the combination, with a punch or the like, of a plate movable relative to the punch, work-centering means carried by the plate, distance-indicating means pivotally and slidingly carried by the plate, and means for indicating the angularity of the distance-indicating means relative to the centering means.
- 105 110 19. In gauging apparatus, the combination, with a punch or the like, of a plate spaced therefrom, work-centering means carried by the plate with its axis spaced from the axis of the punch a distance equal to the distance from the axis of the work to the axis of an aperture to be punched therein, and distance-indicating means spaced from the centering means and movable angularly about the same.

20. In gauging apparatus, the combination, with a punch or the like, of a plate spaced therefrom, work-centering means carried by the plate with its axis spaced 5 from the axis of the punch a distance equal to the distance from the axis of the work to the axis of an aperture to be punched therein, and distance-indicating means spaced from the centering means the same distance 10 as that between the axis of the punch and the axis of the centering means and the distance-indicating means being spaced from the punch.

21. In gauging apparatus, the combination, with a punch or the like, of a plate spaced therefrom, work-centering means carried by the plate with its axis spaced from the axis of the punch a distance equal 15 to the distance from the axis of the work to the axis of an aperture to be punched therein, and distance-indicating means spaced from the centering means and from the punch.

22. In gauging apparatus, the combination, with a punch or the like, of a plate spaced therefrom, work-centering means carried by the plate with its axis spaced 25 from the axis of the punch a distance equal to the distance from the axis of the work 30 to the axis of an aperture to be punched therein, and distance-indicating means spaced from the centering means and movable angularly about the same, the plate being movable relative to the punch and 35 carrying with it the centering means and distance-indicating means, the distance-

indicating means being compensatingly movable.

23. In gauging apparatus, the combination, with a punch or the like, of a plate, 40 a movably mounted support carrying the plate for enabling adjustment of the plate relative to the punch, a bar slidingly and pivotally carried by the plate, a distance-indicating pointer carried by the bar, and 45 a work-centering pointer carried by the plate.

24. In gauging apparatus, the combination, with a punch or the like, of a plate, a movably mounted support carrying the plate 50 for enabling adjustment of the plate relative to the punch, a bar slidingly and pivotally carried by the plate, a distance-indicating pointer carried by the bar, a work-centering pointer carried by the plate, 55 and means for indicating the extent of angular movement of the slidably carried bar.

25. In gauging apparatus, the combination, with a punch or the like, of a plate, 60 a movably mounted support carrying the plate for enabling adjustment of the plate relative to the punch, a bar pivotally carried by the plate, a distance-indicating pointer carried by the bar, and a work-centering pointer carried by the plate. 65

In testimony whereof I affix my signature in presence of two witnesses.
